UNITED STATES PATENT OFFICE.

MARK A. WATERHOUSE, OF CHICAGO, ILLINOIS, ASSIGNOR TO AI WATERHOUSE, OF DURHAM, MAINE.

COMBINED BUSTLE AND CORSET.

SPECIFICATION forming part of Letters Patent No. 290,505, dated December 18, 1883.

Application filed May 12, 1883. (No model.)

To all whom it may concern:

Be it known that I, MARK A. WATERHOUSE, a citizen of the United States, residing in Chicago, county of Cook, and State of Illinois, 5 have invented certain new and useful Improvements in Combined Bustle and Corset, of which the following is a specification.

The object of my invention is to provide a corset with a well-defined bustle that can be 10 readily opened or expanded or closed or contracted at will, so as to suit the form or fancy of the wearer, and also to provide a corset that laces in the back with a well-defined adjustable spring-bustle formed with the corset, and 15 adapted to allow the latter to be freely opened in the back, so as to admit of both the corset and the bustle being adjusted to the form of the wearer without detaching the bustle. These objects I attain by constructing a corset 20 that laces in the back with a two-part spring-bustle having its meeting edges adapted to be laced together, as hereinafter described and claimed, and illustrated in the annexed drawings, in which—

25 Figure 1 represents a corset provided with a bustle in accordance with my invention and fitted upon the figure of a woman. Fig. 2 is a perspective view of one of the halves of the corset and bustle; Fig. 3, a similar view of the remaining half, with a portion of the corset broken away.

30 A denote the two halves of a corset, provided along their rear meeting edges with eyelets or other analogous devices for a lacing, B, by means of which the corset can be laced in the back.

The corset is constructed with a two-part bustle, C, one of which said parts is formed integral with each one of the parts or halves A 40 of the corset. The line of junction between the two halves of the bustle and the two halves or parts of the corset is somewhat above the lower edge of the latter, whereby space shall be left between the corset and the bustle for springs 45 adapted to hold the bustle out from the corset, and to preserve the shape of the bustle under all circumstances.

As herein shown, the springs D consist of flat strips of spring metal secured in any suitable way at one end in pockets in the corset-back, and at their outer ends coiled, so as to

increase their efficiency, and arranged to bear against the inner sides of each half of the two-part bustle.

The meeting edges of the two-part bustle are 55 in line with, or can, as herein shown, project somewhat beyond, the back meeting edges of the corset, and are provided with eyelet-holes, or with other suitable means for receiving or holding a lacing, F, whereby when the corset is 60 laced up in the back the meeting-edges of the two-part bustle can also be similarly laced together, and thus the halves or parts of the bustle be durably and substantially connected with each other.

65 It will be seen that the corset can be opened to any desired extent in the back, and the bustle opened and consequently expanded to a corresponding degree by loosening the lacing between its two halves, and that after being 70 thus expanded it will still preserve its symmetry and present a complete and well-defined bustle, since each half is maintained in a distended condition by the springs, and the parts still connected together by the lacing.

75 The form of springs herein shown is obviously convenient and conducive to the preservation of the shape of the bustle, since the latter can rest upon the coiled ends of the springs. I do not, however, confine myself to the precise construction of springs shown, since the spring-strips could be bent in a variety of ways; or coiled springs could be used.

80 The corset can be adjusted above the bustle by opening or closing it in the back above the point where the lacing for the bustle is located, and hence a perfect fit obtained.

85 By the above construction there will be no liability of the accidental detachment or shifting of the bustle, since while it stands out from the corset it forms a part of the same, and yet is susceptible of expansion or contraction to suit the figure of the wearer and to be opened conjointly with the opening of the corset in the back.

90 I do not consider it necessary to enter into a detailed description of the exact way in which a section of the corset and of the bustle are formed in one piece, since such can be accomplished in a variety of ways that will readily suggest themselves to the manufacturer. The bustle, however, comprises a portion of the

fabric employed in making the corset, and both the corset and the bustle can be strengthened or stiffened with ribs or stays in any desired manner.

5 Instead of lacing the corset in the back, it may be fastened in any other desired manner, but preferably so as to be adjustable, without departing from the spirit of my invention.

Having thus described my invention, what 10 I claim, and desire to secure by Letters Patent, is—

1. The combination, with a corset laced or fastened in the back, of a two-part bustle constructed with the corset and adapted to be expanded or contracted, substantially as described.

2. A corset adapted to lace in the back, and constructed with a two-part bustle having its meeting edges adapted to be laced together, 20 substantially as described.

3. A spring-bustle for a corset, composed of

two parts respectively constructed with the two halves or parts of a corset that is adapted to be laced in the back, substantially as described.

4. The combination, with a corset adapted to lace in the back, of the two-part bustle having its halves respectively made integral with the halves of the corset and adapted to be laced together, and the springs located between the 30 bustle and the lower back portion of the corset, substantially as described.

5. The combination, with a corset that laces in the back, of the two-part bustle constructed with the corset, and the springs D, composed of strips of spring metal secured to the corset under the bustle, substantially as described.

MARK A. WATERHOUSE.
